UNITED STATES PATENT OFFICE.

HENRY M. BRADY, OF DALTON, ILLINOIS.

SMOKE AND GAS CONSUMING FURNACE.

SPECIFICATION forming part of Letters Patent No. 294,007, dated February 26, 1884.

Application filed November 5, 1883. (No model.)

To all whom it may concern:

Be it known that I, HENRY M. BRADY, of 5
Dalton, in the county of Cook and State of Illinois, have invented certain new and useful
Improvements in Smoke and Gas Consuming
Furnaces, of which the following, in connection
with the accompanying drawings, is a
specification.

In the drawings, Figure 1 is a longitudinal
10 vertical central section of a boiler-furnace con-
taining my improvements. Fig. 2 is a section
in the plane of the line $x x$ of Fig. 1, viewed
in the direction indicated by the arrows there
shown. Fig. 3 is a detail showing the slides
15 for regulating the entrance for cold air. Fig.
4 is a section in the plane of the line $x' x'$,
viewed from above; and Fig. 5 is a sectional
detail showing the air-funnels.

Like letters of reference indicate like parts.
20 A represents the furnace, and B is the boiler.
C is the dome. D, D', and D" are bridge-
walls. E is the fire-box. F is a space or open-
ing over the wall D. G is a like space or arch
underneath the wall D', and H is a like space
25 over the wall D". I is the hot-air chamber.
J is a box, made preferably of cast-iron, and
located in the wall D'. a is a partition divid-
ing the box J into two compartments, and a'
a' are perforations in the said partition. This
30 box extends at one end through one of the
side walls of the furnace, as indicated at b in
Figs. 2, 3, and 4, and K K are slides closing
the projecting ends of the said box more or
less, as may be desired. L is a steam-pipe
35 passing from the dome into one of the cham-
bers of the box J, and that chamber is there-
by heated, and may be termed the "hot-air
chamber" of the said box. The other cham-
ber may be termed the "cold-air chamber" of
40 the said box. These two chambers I have des-
ignated by the letters M and N, respectively.
In the chamber M are funnels O O, the larger
ends or mouths of which are in the said cham-
ber, and the smaller ends of which extend
45 through the outer side of that chamber, as is
indicated in Figs. 1, 4, and 5. The pipe L
passes through the funnels O O, and is closed
at its inner end. P P are nipples extending
50 from the pipe L outwardly through the fun-
nels O O.

The furnace is stoked or supplied with coal
in the usual manner, and after combustion be-

gins the heat, gases, particles of carbon, and
other matter there unconsumed pass over the
bridge-wall D, under the bridge-wall D', and 55
into the chamber Q, between the bridge-wall
D' and D". In the chamber Q the products
of combustion referred to meet the horizontal
sheet of steam or vapor escaping from the nip-
ples P P, and also meet a blast of air escap- 60
ing from the funnels O O. The tendency of
these steam-jets and of this injection of air is
to retard the unconsumed products of com-
bustion in their passage through the furnace,
so that they will be exposed longer than oth- 65
erwise to the action of the heat before escap-
ing. The air also, being supplied at this point,
aids combustion by furnishing a new supply
of oxygen. The heat, however, passes the
steam-jets and air-blast and escapes over the 70
wall D" into the chamber I, and passes thence
out and through the boiler-flues and smoke-
stack and chimney. The result of this tortu-
ous course of the heat and particles which con-
stitute what is commonly termed "smoke," 75
and of the impingement upon these particles
of the steam and air, before referred to, causes
a much more complete combustion of the said
particles than would otherwise occur, and the
chimney will be comparatively if not entirely 80
smokeless. The escape of steam through the
nipples P P may be regulated by means of a
cock in the pipe L, and the entrance of air may
be controlled by means of the slides or doors
K K. It will be perceived that a volume of 85
air will enter the chamber N directly from the
outside of the furnace, and pass thence through
the perforations a' a' into the chamber M,
where it becomes heated to a greater or less
degree before passing out through the funnels 90
O O. It will also be perceived that a volume
of air may be admitted directly into the cham-
ber M through its slide or door K, the said air
being inducted by suction.

Having thus described my invention, what I 95
claim as new, and desire to secure by Letters
Patent, is—

1. In a boiler-furnace, the combination of
the boiler, the fire-grate, the two bridge-walls
with passages thereover, the intermediate 100
bridge-wall having a passage thereunder, the
transverse air-chamber located in the inter-
mediate wall, means for controlling the ad-
mission of air into said chamber, and steam-

ejector nozzles located in said chamber, and arranged, as described, to deliver the air in a backward direction.

2. In a boiler-furnace, a bridge-wall provided with a transverse air-chamber divided longitudinally, as described, into two compartments, in combination with means for controlling the admission of air to said compartments independently, a steam-pipe provided with nozzles, and located in the rear compartment, and nozzles O, also located in said compartment and arranged to deliver the air in a backward direction, as described.

3. In a boiler-furnace, a bridge-wall provided with a transverse air-passage divided longitudinally into two communicating compartments, the rear compartment being provided with a steam-pipe and with nozzles, as described, for delivering the air in a backward direction.

4. The combination, in a furnace, of the bridge-wall D, having over it the space or

passage F, and the wall D', having under it the space or passage G, and a steam-injector arranged in an air-supplying chamber, the said injector and air-supplying chamber communicating with the chamber behind the wall D', substantially as and for the purposes set forth.

5. The combination, in a furnace, of the bridge-wall D, having over it the space or passage F, the bridge-wall D', having under it the space or passage G, the bridge-wall D'', having over it the space or passage H, and the box J, located in the wall D', and containing the chambers N and M, with their slides or doors K K, the said chambers being separated by means of a perforated partition, and the chamber M containing the injector L P and the funnels O O, substantially as and for the purposes specified.

HENRY M. BRADY.
